Filed Dec. 17, 1957, Ser. No. 703,439

5 Claims. (Cl. 160—354)

My invention relates to swinging doors of the type comprising a panel of flexible material.

Doors of the above type, which are described in my United States Patent No. 2,279,572, comprise a frame in the form of an inverted L to which is supported along one side edge and the top edge, a flexible panel consisting of a sheet of flexible material, such as rubber, or plastic. In another type of construction, which is less flexible, the panel comprises a bulky envelope of flexible material, such as rubber, stuffed with hair. Such stuffed panels are to some extent self-supporting and, provided the door is not too wide, the top edge need not be so supported by a separate frame member.

Although doors of the above type have proved to be satisfactory and have come into extensive use, I have found that under some conditions, they have certain disadvantages. More particularly, if the panel is given sufficient flexibility to obtain all the advantages of this type of door, it is difficult, under some conditions, to maintain the free or unsupported edges of the panel in their proper positions when the door is in its closed position. This difficulty may be caused by a difference in air pressure on the sides of the door, to wind pressure and, when the door is of the stuffed type, to temporary deformation of the bulky panel. These difficulties are mainly prevalent at the lower unsupported corner of the panel, but they also occur along the unsupported edges.

In my United States Patent 2,783,833 I have described an articulated stiffening member which to a large extent eliminates these difficulties. However, such stiffening members are rather expensive, bulky and are subject to damage when hit by trucks using the door.

The main object of my invention is to provide such doors with stiffening members of such a construction that, when the door is in its closed position, the flexible panel and particularly the free edges thereof are maintained in their proper positions under various adverse conditions such as mentioned above.

A further object is to increase the stiffness of a portion of the door panel without decreasing its resiliency.

Another object is to provide a stiffening member which also serves as a readily-replaceable protective member.

A still further object is to provide a stiffening member whose stiffness decreases sharply when it is bent more than a certain amount.

According to the invention I provide the flexible panel of such a door with a stiffening member having at least one corrugation extending from the supported side edge of the panel toward one of the unsupported edges and which member is fixedly secured to the side portion of the frame near one end of the corrugations and is secured to the panel along the troughs of the corrugation.

In a preferred embodiment of my invention the stiffening member is in the form of a sheet of flexible material, such as rubber, plastic, or thin metal, provided with a plurality of parallel corrugations extending across the sheet. Such a sheet has one edge fixedly secured to the

2

side portion of the frame and is secured to the panel at points along the troughs of the corrugations, preferably so as to permit a small amount of movement of the sheet relative to the panel in the direction of the corrugations.

In another preferred embodiment, I make the stiffening member of a sheet of rubber reinforced with fabric and mould in the corrugations leaving a flat strip along one edge for securing the member to the side portion of the frame.

In order that my invention may be clearly understood and readily carried with effect I shall describe the same in more detail in connection with the accompanying drawings in which:

Figure 1 is a side-view of a door embodying my invention.

Figure 2 is a sectional view on an enlarged scale taken along line 2—2 of Figure 1.

Fig. 3 is a sectional view on an enlarged scale taken along line 3—3 of Figure 1.

Fig. 4 is a sectional view on an enlarged scale taken along line 4—4 of Figure 1.

Fig. 5 are sectional views of stiffening members of different shapes.

Fig. 6 is a side-view of a door according to a preferred embodiment of the invention.

Fig. 7 is a sectional view along line 7—7 of Figure 6, and

Fig. 8 is a sectional view on an enlarged scale along line 8—8 of Figure 6.

The door shown in Figure 1, which is basically of the construction described in my U.S. Patent 2,279,572, comprises an inverted L-shaped frame 10 to the top and one side of which is secured a sheet 11 of flexible material, such as rubber or plastic, which forms the panel. The side of frame 10 is provided at the top and bottom with pivoting means and with spring means (not shown) which return the door to its closed position. As such means are well known in the art and are described in my above-mentioned Patent No. 2,279,572, further description and illustration of the same is believed to be unnecessary.

In accordance with the invention the panel 11 is provided with three stiffening members 12 which are secured to the panel along the troughs of the corrugations by means of rivets 13 (see Fig. 2) and have one end secured to the frame 10 by means of rivets 16 (see Fig. 3). As shown the stiffening members are provided on both sides of the panel, which is preferable, but in some cases it is sufficient to place them on only one side.

As shown more clearly in Figure 4 the members 12 are provided with slots 14 for the rivets 13 to thereby permit a small movement of the stiffening members relative to the panel in the direction of the corrugations.

One end of each of the members 12 is fixedly secured to the frame 10 (see Fig. 3) by means of curved metal clamps 15 and 17 and rivets 16.

While I have shown the stiffening members 12 secured to the panel 10 by means of rivets 13 and 16, it is preferable in many instances to use bolts or other types of removable fasteners which are well-known in the art.

The stiffening members maintain the flexible panel flat when the door is not in use and, as their ends are firmly secured by clamps to the frame 10, they hold the free edges of the panel in their proper positions when the frame is in the closed position. These members also increase the stiffness of the panel without appreciably decreasing its resiliency. This is due to the cross-sectional shape of the stiffening members which causes

the resistance to bending to decrease when the angle to which the members are bent exceeds a certain amount,

i.e. when the members buckle. Due to the corrugated shape, which may have various forms, such as shown in Fig. 5, the stiffening members also serve effectively to protect the flexible panel from damage due to the impact of trucks, etc.

A particularly advantageous construction according to my invention is illustrated in Figures 6, 7 and 8 in which the reference figures of the previous figures are used to indicate the same parts. As shown in Figure 6 the lower portion of the flexible panel is provided on each side with a sheet or apron 18 of rubber re-enforced with fabric. The sheet has molded therein a number of corrugations 19 which extend from the unsupported edge of the panel to a point spaced from the supported edge to thereby provide a flat securing portion 23 for clamping the sheet to the frame. As shown in Figure 8 the sheets 18 are secured to the flexible panel 11 at several points along the trough of each corrugation by means of rivets 13. To permit a small amount of movement of sheets 18 with respect to panel 11 the rivets 13 pass through slots in sheets 18.

With reference to Figure 7 the frame 10 has welded to it a metal channel 20 whose width is the same as the distance between the flat securing portions 23 of sheets 18. The portions 23 are clamped to channel 20 by means of bolts 21 and metal strips 22. It will be noted from Figure 6 that the corrugations 19 extend to the edge of strip 22. This clamping construction has the advantage over that of Figure 1 that the curved clamps 15 and 17 are eliminated.

While I have described my invention in connection with specific examples and constructions, I do not desire to be limited thereto as obvious modifications will readily present themselves to one skilled in this art.

I claim:

1. A door comprising a frame having a side portion adapted to be pivotally supported and a top portion, a flexible panel supported at its top and one side edge from said frame, stiffening means comprising a flexible sheet having one end fixedly secured to said side portion and forming a plurality of corrugations extending from the fixedly-secured end of the sheet toward an unsupported edge of the panel and means securing said member to said panel along the troughs of the corrugations.

2. A door comprising a frame having a side portion adapted to be pivotally supported and a top portion, a flexible panel supported at its top and one side edge from said frame, a stiffening member of flexible material having one end fixedly secured to said side portion and pro-

vided with a plurality of corrugations extending from said side edge toward an unsupported edge of the panel and means securing said member to said panel along troughs of the corrugations while permitting a small amount of movement relative to the panel.

3. A door comprising a frame having a side portion adapted to be pivotally supported and a top portion, a flexible panel supported at its top and one side edge from said frame, stiffening means comprising a flexible sheet forming a plurality of corrugations extending from the supported side edge toward an unsupported edge of the panel, means fixedly clamping said stiffening means to the side portion of said frame at one end of the corrugations and means securing said stiffening means to said panel at points along the troughs of said corrugations while permitting some movement of the corrugation relative to the panel.

4. A door comprising a frame having an upper portion and a side portion adapted to be pivotally supported, a flexible panel supported at its top and one side edge from said frame, a stiffening member in the form of a flexible sheet provided with a plurality of molded corrugations each having one end spaced from one end of the sheet to form a supporting portion, means fixedly securing the supporting portion of said sheet to the side portion of the frame with the corrugations extending toward an unsupported edge of the panel and means securing said sheet to said panel at points along the troughs of the corrugations.

5. A swinging door comprising an inverted L-shaped frame having an upper portion and a side portion, a panel comprising a sheet of flexible material supported at its top and one side from said frame, a protective stiffening member comprising a sheet of flexible material provided with a plurality of molded corrugations having one end spaced from one edge of the sheet to form a flat securing portion, means clamping the securing portion of said sheet to the side portion of the frame with the corrugations extending toward the unsupported edge of the panel, and means securing said sheet to the panel at points along the troughs of the corrugations while permitting a small amount of movement of the sheet relative to the panel in the direction of the corrugations.
